UNITED STATES PATENT OFFICE.

GEORGE H. WHITTINGHAM, OF BALTIMORE, MARYLAND, ASSIGNOR TO MONITOR CONTROLLER COMPANY, OF BALTIMORE, MARYLAND, A CORPORATION OF MARYLAND.

RHEOSTAT.

Application filed March 23, 1925. Serial No. 17,628.

This invention relates to improvements in the type of rheostat illustrated in my co-pending application Serial No. 725,555, filed July 12, 1924, in which edgewound resistance coils are mounted upon supporting members each composed of a metal bar having a covering of refractory insulating material provided with threads for receiving the coil, the covering for the bar being composed of 5 relatively short sections arranged end to end and interlocking with the bar. The present invention embodies improvements in the manner of mounting the sections of insulating material upon the bars which carry the coils; 10 also to details of the rheostat frame and the means for mounting the coil supporting bars therein.

In the accompanying drawing,

Fig. 1 is a top plan view, partly broken away, of a rheostat made in accordance with my invention;

Fig. 2 is a side elevation of the same, partly in section, on the line 2—2 of Fig. 1;

Fig. 3 is an end view of the rheostat, looking from left to right in Figs. 1 and 2;

Fig. 4 is a side view of one of the coil supporting bars;

Fig. 5 is a perspective view of two of the sections of the covering for the coil supporting bars;

Fig. 6 is a section on the line 6—6 of Fig. 1, showing in detail the manner in which the coil supporting bars are mounted on the cross bars of the frame; and,

Fig. 7 is a perspective view showing the elements composing the frame of the rheostat.

In the accompanying drawing, *a* and *a'* indicate two similar frames, one supported upon the other, and each frame supporting a plurality of resistance units, indicated at *r* in the frame *a*, and at *r'* in the frame *a'*. Each resistance unit comprises a flat metal supporting bar *b*, shown in side view in Figs. 2 and 4, an insulating covering *c* of refractory material, and a resistance coil *d*, threaded on to said covering. Each supporting bar *b* has a forked end 1 and a hooked end 2. The bar also has shoulders 3 and 4, at its opposite edges adjacent the forked end 1, and it has similar shoulders 5 and 6 adjacent the end 2. The shoulder 3 is offset from the shoulder 4, and the shoulder 5 is offset from the shoulder 6, and the distance between the shoulders 3 and 5 is the same as the distance between the shoul-

ders 4 and 6. The covering *c* is composed of 55 relatively short and flat sections of refractory material, preferably porcelain, of the form illustrated in Fig. 5, wherein are shown two opposing pieces 7 and 7^a. These pieces of material are alike in all respects. Each 60 has a deep groove 7^b, extending inwardly from one edge, and each has a plurality of threads or teeth 7^c on its opposite edge. The sections of insulating material fit over the edges of the bar, and in placing these sections upon the 65 bar, two sections, such as 7 and 7^a, in Fig. 2, are placed against the shoulders 3 and 4, respectively, and the other sections 8, 9, etc. on one edge of the bar are arranged end to end, and the sections 8^a, 9^a, are arranged end to 70 end on the opposite edge of the bar so that two series of opposing sections are built up upon the bar to any desired length. The shoulders 3 and 4 are off-set from one another 75 longitudinally of the bar one-half the distance between the centers of adjacent teeth on one of the porcelain sections, so that when the covering is on the bar, the threads on the sections 7, 8, 9, etc., will be offset from the threads 7^a, 8^a, 9^a, etc. the proper distance to 80 receive the convolutions of the helix *d*. It will be seen that by providing the offset shoulders on the bar and by placing the end sections of the insulating material against these shoulders, the threads on all of the sections 85 will be properly placed to receive the helix. To facilitate applying the sections of insulating material to the supporting bar, I preferably apply to the opposite sides of the bar thin layers 10 of asbestos, which are secured 90 by suitable cement, and when the porcelain sections are applied to the bar, they are held thereon frictionally and adhesively by the asbestos and cement. The coils are composed 95 of flat ribbons of metal wound on edge and these are readily applied by threading them on to the covering. This may be accomplished by turning either the coil or the bar in a lathe.

Each of the frames *a*, *a'*, for supporting 100 the assembled resistance units, is composed of two flat side bars 11, connected at their ends by bolts or end bars 12, and these bolts pass centrally through flat frame supporting bars 13, which extend at right angles to the side bars and have their ends 13^a turned over at right angles to their body portions and in the same direction. The end bars or bolts

12, as shown in Fig. 6, are covered by a tube 14 of insulating material, preferably mica. The forked ends 1 of the coil supporting bars fit over the insulating tubing on one of the 5 bolts 12, and the hooked ends 2 of the side bars rest upon the insulating tubing upon the other bolt 12. Washers 15 of insulating material are placed on each side of the ends of the bars 6, and these bars are spaced apart 10 by sections of metal tubing 16 and by metal washers 17 which are arranged between the ends of the spacing tubes and the insulating washers 15. The bolts 12 are provided with nuts 18 at their ends, and by tightening these 15 nuts the spacing tubes will be forced together and the coil supporting bars will be firmly held in position. The tightening of these nuts also tightens the members of the frames.

The side bars of the frames are alike in 20 form and each has overturned ends 11^a, which bear against the edges of the frame supporting members 13 and hold these in their upright positions before the nuts 18 are tightened. The members 13 also are all alike. 25 It will be seen that the supporting frames are composed of few parts, and that a frame to suit any desired number of coils can be quickly assembled by selecting end bolts of a length to suit the number of coils and bolt- 30 ing the parts together.

The overturned ends 13^a on the supports 13 serve as a means for connecting a plurality of frames together. Thus, as shown in Fig. 3, the frames *a* and *a'* are secured together by bolts 19 passing through the adjacent overturned ends of the members 13 on both frames. As many frames as desired may be thus secured together. In connecting a number of frames together, the nuts 18 on the end bolts or bars are not firmly tightened until 40 the frames are assembled. After the members 13 in the several frames have been properly lined up and bolted together, the nuts on the end bolts may be tightened and the whole structure will then be a rigid frame 45 composed of several similar frames.

In the drawing, I have shown terminal clamps *t* on some of the coils and connectors *t'* between adjacent coils, but these features need not be described herein as they are not 50 a part of the present invention but are claimed in my co-pending application referred to above.

While I have shown a pair of offset shoulders or stops, 3—4, at one end of each coil-supporting bar, and a similar pair 5—6 at the opposite end, so that the operation of assembling the porcelain parts may be commenced at either end of the bar, it will be 55 obvious that only one pair of shoulders is essential for correctly positioning the porcelain parts on the bar, and that the other pair may be omitted.

What I claim is:

1. In a rheostat, a metal bar having a 65 threaded insulating covering thereon adapted to receive a helix of resistance metal, said covering comprising opposed sections having threads on their outer edges, and said bar having stops offset from one another longitudinally of the bar for positioning said sections so that the threads on one section will be a definite distance in advance of the threads on an opposing section. 70

2. In a rheostat, a metal bar having a relatively flat threaded insulating covering thereon adapted to receive a helix of resistance metal, said covering comprising two opposing series of like sections having threads on their outer edges and said bar having stops offset from one another longitudinally of the bar for positioning the end section of one series a definite distance in advance of the corresponding section of the opposing series. 75

3. In a rheostat, a flat metal bar having 80 shoulders on its opposite edges, near one end, and offset from one another longitudinally of the bar, an insulating covering for the bar comprising two opposing series of like sections, each section channeled to fit the bar and having threads on its outer edge, and the end section of each series fitting against one of 85 said shoulders. 90

4. In a rheostat, a pair of similar flat metal strips, constituting side bars, frame-supporting members comprising similar flat metal strips arranged at right angles to the side bars, said members having their ends turned at right angles to their central portions, bolts 95 extending through the central parts of said members and through the end portions of the side bars, spacing members on the bolts, coil-supporting bars having their ends supported by the bolts between the spacing members and insulated from the bolts, and means on the 100 ends of the bolts for clamping the various parts on the bolts together. 105

5. In a rheostat, a pair of similar flat metal strips, constituting side bars, each strip having flanges at its ends, frame-supporting members comprising similar flat metal strips arranged at right angles to the side bars and against said flanges, said members having their ends turned at right angles to their central portions, bolts extending through the 110 central parts of said members and through the end portions of the side bars, spacing members on the bolts, coil-supporting bars having their ends supported by the bolts between the spacing members and insulated 115 from the bolts, and means on the ends of the bolts for clamping the various parts on the bolts together. 120

In testimony whereof I hereunto affix my signature.

GEORGE H. WHITTINGHAM.
